Primary Examiner — Dominic V Simone**(57) CLAIM**

The ornamental design for a shoe upper, as shown and described.

DESCRIPTION

FIG. 1 is a perspective view of a shoe upper showing our new design;

FIG. 2 is a top plan view thereof;

FIG. 3 is a left side view in elevation thereof;

FIG. 4 is a right side view in elevation thereof; and,

FIG. 5 is a front view in elevation thereof.

The broken line illustration of environmental structure in the drawings is not part of the claimed design.
